UNITED STATES PATENT OFFICE.

FRED LOBNITZ, OF RENFREW, SCOTLAND.

DISCHARGE-DOOR OF HOPPER DREDGERS AND BARGES.

No. 905,338.

Specification of Letters Patent.

Patented Dec. 1, 1908.

Application filed June 29, 1906. Serial No. 324,049.

To all whom it may concern:

Be it known that I, FRED LOBNITZ, of Clarence House, Renfrew, Scotland, engineer and shipbuilder, a subject of the King of Great Britain, have invented certain new and useful Improvements Relating to the Discharge-Doors of Hopper Dredgers and Barges, of which the following is a specification.

10 This invention relates to hopper dredgers and barges and it has for its object to provide improved mechanism or gear for manipulating the discharge doors thereof.

It is very important to be able to raise 15 and lower the discharge doors simultaneously with the minimum expenditure of time and trouble and it is equally desirable that when the doors are closed they should be held fast without continuous strain being 20 put on the manipulating mechanism.

25 My invention is designed to effect this object by mechanism so constructed and arranged that all the doors can be raised and lowered simultaneously and when raised can be held fast by simply driving a single wedge into position. The wedges take the strain off the manipulating mechanism.

30 In the drawing annexed, Figure 1 shows part of a barge with the hopper in section and Fig. 2 is a plan of the same. These figures show the method of carrying out the invention. Fig. 1^a is an enlarged sectional elevation of the operating mechanism. Fig. 2^a is a sectional plan thereof.

35 On the drawings the same reference letters wherever repeated indicate the same or similar parts.

When carrying out my invention in accordance with the arrangement shown at 40 Figs. 1 to 1^a, I connect the hopper doors *a* by means of chains *b* to cross bars *c* which are connected to chains *e* passing over pulleys *f*. Each chain *e* is connected to a cross piece *g* and these pieces are fitted rigidly to 45 and between horizontal bars *h*, *h*¹, adapted to slide in guides on the upper surface *i* of the hopper girder *j*. The bars *h*, *h*¹, are, at their front ends, connected together and to the block *k* (these parts are also clearly indicated at Figs. 1^a and 2^a) which latter has a screw *l* whose outer end is inclosed in a tubular casing *m*. On the screw is fitted an elongated nut *l*¹ having external collars *l*² working in grooves in a thrust block *l*³ which 50 latter is rigidly connected to the pedestal *l*⁴.

Keyed on the nut *l*¹ is a worm wheel *n* which is revolved by a worm *n*¹ Figs. 1 and 1^a, on a shaft *o* driven by the gear *o*¹ from the engine shaft *p* of the maneuvering winch of the barge or dredger. The engine shaft *p* 60 drives the winch drum shaft *p*⁰ by the gear *p*¹.

*p*² is a lever for operating a sliding clutch *p*³ on the shaft *p* for the purpose of throwing gear *p*¹ out or in as desired. 65

The maneuvering winch is of the usual construction with the exception that its engine is, as aforesaid, adapted to also rotate the worm wheel *n* and thereby raise and lower the hopper doors. As the worm wheel and nut *l*¹ are held in position it follows 70 that when the latter is revolved, one way or the other, it, of course, works the screw *l* backwards or forwards and thereby operates the bars *h*, *h*¹ and chains *e*, *b*, so as to open 75 or close all the hopper doors *a* simultaneously. When the doors are closed, the block *k*, and consequently the bars *h*, *h*¹, is held in position by a single wedge or pin *q* which is driven through the holes *q*¹ in the housing 80 *r*¹ and a hole in the block. With this arrangement the advantage is that there is but a single wedge for holding all the doors and that the winch engine, and this wedge, can be attended to by one man on the spot. 85

It will be seen that the usual lifting chains *b* are carried up through hollow or tubular trunks *b*¹, suitably secured in the hopper.

The fact that the several doors are hung 90 by chains attached at each end thereof and that these chains are carried up in trunks is a decided advantage especially when discharging rock and other materials which tend to bridge, because, when the doors are let go, they are sure to drop as the chains work through the tubular trunks without coming in contact with the spoil in the hopper. 95

Having now fully described my invention 100 what I claim and desire to secure by Letters Patent, is:—

1. In hopper dredges and barges having discharge doors, the combination with the said doors, of means for raising and lowering all of them simultaneously, and a single pin adapted to simultaneously lock all the 105 said doors when in the raised position.

2. In hopper dredges and barges having discharge doors, the combination with the said doors, of mechanical means for raising 110

and lowering all of them simultaneously, and a single pin adapted to simultaneously lock all the said doors when in the raised position.

5. In hopper dredgers and barges having discharge doors, the combination with the doors thereof, of movable bars, means connecting the bars to the doors, a block with a slot therein, means for moving the block, 10 and a wedge which can be driven through the block so as to simultaneously hold all the doors fast.

4. In hopper dredgers and barges having discharge doors, the combination with the 15 doors thereof, of slide bars, means connecting the doors to the slide bars, guides for the bars, a block, a guide for the block, means for operating the block and a wedge for simultaneously holding the block and all 20 the doors fast.

5. In hopper dredgers and barges having discharge doors, the combination with the doors thereof, of slide bars, means connecting the doors to the slide bars, guides for the 25 bars, a block, a guide for the block, screw and nut gear for operating the block and a wedge for simultaneously holding the block and all the doors fast.

6. In hopper dredgers and barges having discharge doors, the combination with the 30 doors thereof, of slide bars, means connecting the doors to the slide bars, a block connected to the slide bars and having a slot therein, a wedge for locking all of the doors 35 simultaneously, a screw connected to the block, and mechanism for operating the screw.

7. In hopper dredgers and barges having discharge doors, the combination with the 40 doors thereof, of slide bars, means connecting the doors to the slide bars, a block connected to the slide bars, a housing for the block, a thrust block, a wedge for locking all of the doors simultaneously, a screw connected to the block and passing through the 45 thrust block, and means for operating the screw.

8. In hopper dredgers and barges having discharge doors, the combination with the 50 doors thereof of slide bars, guides for the

slide bars, means connecting the doors to the slide bars, a block connected to the slide-bars and having a hole therein, a housing for the block, said housing having holes at each side thereof, a wedge capable of being passed through the holes in the housing and the block, a thrust block, a screw connected to the first mentioned block, an elongated nut on the screw and within the thrust block, a worm wheel on the nut and means for rotating the worm wheel.

9. In hopper dredgers and barges, the combination with the doors thereof of slide bars, guides for the slide bars, chains connecting the doors to the slide bars, trunks 65 for the chains, a block connected to the slide bars and having a hole therein, a housing for the block, said housing having holes at each side thereof, a wedge capable of being passed through the holes in the housing and the 70 block, a thrust block, a screw connected to the first mentioned block, an elongated nut on the screw, and within the thrust block, a worm wheel on the nut and means for rotating the worm wheel.

10. In hopper dredges, the combination with each door thereof, of means arranged at each side of the door for raising and lowering the same, means for operating the said raising and lowering means, and a 80 wedge adapted to lock the same in raised position and to lock all of the doors simultaneously.

11. In hopper dredges and barges, a plurality of doors, means for raising and lowering said doors, and a pin co-operating with said means for simultaneously locking all 85 the doors.

12. In hopper dredges and barges, a plurality of doors, means for raising and lowering said doors, and a wedge-shaped pin co-operating with said means for simultaneously locking all the doors.

In testimony whereof I affix my signature in presence of two witnesses.

FRED LOBNITZ.
